ADJUSTABLE MEANS FOR ATTACHING
QUILTS, BLANKETS, ETC., TO CRIBS

Arthur Bleier, New York, N. Y.

Application August 25, 1936, Serial No. 97,719

2 Claims. (Cl. 5—320)

This invention relates to new and useful improvements in an adjustable means for attaching quilts, blankets, etc., to cribs.

The invention has for an object to associate fastening elements upon said quilt or similar article spaced in from the edge portions thereof and associated with strips having at their ends coacting fasteners for releasable attachment on said quilt or similar article.

0 Still further the invention contemplates the provision of gripping elements on the other ends of said strips and adapted to engage certain of the vertical rods in the sides of a crib so as to permit the quilt to move vertically, but restrained from lateral motion.

A feature of the arrangement resides in the fact that the quilt or similar article will be restrained from slipping off from a child laying in the crib, while at the same time it may move vertically to permit turning and tossing during sleep.

20 A further feature of the invention resides in an arrangement whereby the strips are attached to the edge portions of the quilt or other article in a manner so as to permit the edge portions to continually extend downwards over the sides of 25 the mattress of the crib in all vertical positions of the quilt or similar article.

Another one of the objects of the invention resides in the specific construction of the gripping elements to adapt them for convenient operation.

30 Still further the invention contemplates arranging the strips from elastic material so as to be automatically adjustable to fit the quilt to cribs of varying widths.

35 Another one of the objects resides in a provision which permits the strips to be adjusted longitudinally along the length of the quilt or similar article so that they may be properly located to engage the vertical bars of the side 40 portions of the crib.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

50 Fig. 1 is a perspective view of a crib with a quilt and a holding means constructed according to this invention.

Fig. 2 is a transverse sectional view of the quilt, this view being as though taken on the line 2—2 of Fig. 3.

55 Fig. 3 is a plan view of the quilt and the adjustable holding means therefor.

Fig. 4 is a fragmentary enlarged detailed view 60 of one of the corners of the quilt shown in Fig.

3, but showing a modified form of the fastening element.

Fig. 5 is a sectional view taken on the line 5—5 of Fig. 4.

Fig. 6 is an elevational view of a strip of fastening element constructed according to this invention.

Fig. 7 is a sectional view taken on the line 7—7 of Fig. 6.

Fig. 8 is a fragmentary view similar to Fig. 4 but illustrating a modification of the invention.

Fig. 9 is a fragmentary enlarged sectional view taken on the line 9—9 of Fig. 8.

Fig. 10 is another view similar to Fig. 4 but illustrating a still further modified form of the invention.

Fig. 11 is a sectional view taken on the line 11—11 of Fig. 10.

Fig. 12 is a fragmentary perspective view, illustrating a still further modified form of the invention.

Fig. 13 is a fragmentary enlarged detail view of one of the corners of the quilt shown in Fig. 12.

Fig. 14 is a vertical sectional view, taken on the line 14—14 of Fig. 13.

The adjustable means for attaching quilts, blankets and the like to cribs is intended for cooperation with a crib 10 having a plurality of vertical side rods 10^a. In all respects the crib is of conventional construction and for this reason the details thereof will not be given in this specification. The reference numeral 11 indicates generally a quilt or blanket or similar article. Fastening elements 12 (see Figs. 3 and 5) are arranged upon said quilt 11 spaced in from the edge portions 11^a thereof. Strips 13 have one of their ends coacting with the fastening elements 12 and the other of their ends provided with gripping elements 14 adapted to engage certain of the vertical rods 10^a.

The quilt 11 preferably is of rectangular shape and adapted to engage upon the mattress and covering sheets of the crib. This quilt 11 is adapted to cover a child sleeping in the crib. The fastening elements 12 comprise sections of snap fasteners. These fastening elements 12 coact with complementary fastening elements 12' arranged upon the inner ends of the strips 13. The strips 13 comprise elastic material so as to be stretchable to permit the holding means to engage cribs of slightly different widths. The gripping elements 14 comprise a piece of spring steel or other similar material bent into a specific shape.

As illustrated in Figs. 6 and 7, each of the gripping elements 14 comprises a piece of spring steel formed with a gripping element 14' which consists of a piece of spring wire turned at its central portion into several turns 14^a which form a loop for the elastic 13 to engage therethrough as

previously described relative to the prior form. From the coiled portion 14^a semi-circular portions 14^b project, which terminate in interengageable end portions 14^c. According to this form of the invention it is necessary that the interengaging portions 14^c be forced to disengage each other and then the semi-circular portions 14^b be drawn apart to open them so that the gripping element may be engaged upon a vertical rod of the crib.

10 In Figs. 4 and 5 a slightly modified form of the invention has been disclosed which distinguishes merely in the construction of the gripping elements. According to this form of the invention there is a circular portion 14^a at its center and 15 extended into several turns and forming a loop through which the strap 13 may pass. The strap 13 is of double material engaged at its center through the loop 14^a and secured in position by a line of stitches 13^a. The material of the outer 20 end portion of the strap 13 is secured together by the snap fastener element 12.

From the coiled portion 14^a the gripping element continues into opposed outwardly directed loop portions 14^b, each of which continues into a semi-circular portion 14^c, terminating in interengageable ends 14^d. The interengageable ends are merely partially twisted to engage each other. The portions 14^c are adapted to engage the vertical posts 10^a of the crib. The portions 14^b are adapted to be squeezed together to open the portions 14^c so that the gripping elements may be engaged on the post.

The strips 13 and the associated gripping elements 14 may be removed from the quilt 11 by disengagement of the snap fastener 12 and 12'. The quilt may then be laundered. These parts may be re-engaged when desired, and serve to adjustably hold the quilt in position upon the crib.

In Figs. 8 and 9 a modified form of the invention has been disclosed in which provision is made for adjusting the holding means both laterally and longitudinally. More specifically, the quilt 11 has small strips 16 secured along portions spaced in from the edge portions thereof, and located 45 near the corners or throughout the entire length of the quilt. These strips 16 are secured in position by lines of stitches 17 along the edges thereof. A cord or other fastening element 18 is laced through holes in the strips 16 so as to present a plurality of looped portions 18^a extending along the length of the strips 16.

The ends 18^b of the cord 18 are tied together in a knot. Associated with each cord 18 there is a strip 13' which is adapted to be releasably engaged 55 on any one of the loop portions 18^a. Specifically, the strip 13' has its end portion engaged through one of the loops and is so held in position by snap fastener elements 12^a upon adjacent parts thereof. These snap fastener elements may be opened 60 to permit the strip 13' to be disengaged from the loop 18^a.

A gripping element 14 is mounted on the extended end of the strip 13'. A feature of the construction resides in the fact that the holding 65 means may be shifted longitudinally by engaging the strip 13' through the several loops 18^a. The holding means may be adjusted transversely by opening the knot 18^b of the cord 18 and drawing the cord in or leaving it out, as the case may be.

70 When tension is applied to the holding means, the various loops 18^a will flatten out and disappear, except the one through which the strip 13 is passed. The size of this particular loop may be controlled by leaving out or drawing in of the knot 75 18^b of the cord 18.

In Figs. 10 and 11 another modified form of the invention has been disclosed in which an arrangement is provided by which the holding means may be adjusted longitudinally. A cord or other filling element 20 is forced inwards from the bottom side of the quilt 11 and is secured in this position by a line of stitches 21. The cord 20 is extended longitudinally spaced in from the edge portions of the quilt 11 at the ends thereof. Thus, a projecting portion 22 is formed on the top of the 10 quilt.

A metallic clip 23 is adapted to be clipped on the projecting portion 22 anywhere along its length. This metallic clip 23 is connected with the strip 13, which in turn supports at its outer end the gripping element 14. It will be readily understood that the clip 23 may be shifted to various positions along the longitudinal length of the projected portion 22 and so the location thereof may be adjusted to fit the spacing of the vertical bars 20 11^a of the crib.

In Figs. 12, 13 and 14, a still further modified form of the invention has been disclosed in which a plurality of loops 25 made of a continuous braid, are stitched to a strip 26 at 27. The strip 26 is stitched to the quilt 11, at 28, spaced from the edge portions 11^a. Gripping elements 14' are connected to one end of elastic strips 13'. The other end of each elastic strip 13' is engaged by loop 29 of an anchor pin 30. This anchor pin is 30 pulled through one of the loops 25, for selectively locating the gripping elements 14' at the particular loop 25 which is in the closest vicinity of the desired vertical side rods 10^a. The length of the elastic strips 13' may be adjusted by a suitable adjusting buckle 13^b.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent, is:—

1. In a device of the class described, a bed cover for use on a crib having vertical side rods, strips attached longitudinally of and on said bed cover along the side portions thereof, cords 50 threaded through openings in said strips and having their ends tied together by which loop portions may be formed along the length of said strip by drawing in and letting out portions of said cords, fastening elements engaging through 55 said loop portions at one of their ends and adapted to be connected with said rods at the other of their ends.

2. In a device of the class described, a bed cover for use on a crib having vertical side rods, 60 strips attached longitudinally of and on said bed cover along the side portions thereof, cords threaded through openings in said strips and having their ends tied together by which loop portions may be formed along the length of said 65 strip by drawing in and letting out portions of said cords, fastening elements engaging through said loop portions at one of their ends and adapted to be connected with said rods at the other of their ends, said fastening elements being selectively 70 engageable with various loop portions formed on said strip to align said fastening elements with said side rods so that they may be easily engaged therewith.
